CLAIM

The ornamental design for a ballpoint pen, as shown and described.

DESCRIPTION

FIG. 1 is a side elevational view of the present invention;

FIG. 2 is a front elevational view;

FIG. 3 is a rear elevational view;

FIG. 4 is a top planar view; and,

FIG. 5 is a bottom planar view.

FIG. 1

FIG. 2

FIG. 3

FIG. 4

FIG. 5
